OIL BURNER APPARATUS, INCLUDING AN AUTOMATIC DELAY ACTION FUEL VALVE

Wallace R. Lyman, Chicopee Falls, Mass., assignor to Westinghouse Electric Corporation, East Pittsburgh, Pa., a corporation of Pennsylvania

Application March 27, 1943, Serial No. 480,725

7 Claims. (Cl. 158—36.3)

1

My invention relates to oil burning apparatus and, more particularly, to controlling the flow of combustion air and fuel oil into the combustion chamber of such apparatus.

In conventional oil burners, gear pumps are usually employed for delivering fuel oil to the combustion chamber. This pump and the blower, which supplies the combustion air, are driven by a single motor which is energized by a manually or thermostatically operated switch. Due to the positive displacement of the oil by the quick action of the gear pump, and due to the compressibility and slipping of the air, the gear pump overcomes the resistance to which a conventional cut-off valve and pressure regulator may be set, and the fuel oil reaches the combustion chamber, well before the supply of combustion air reaches its rated or normal flow. This creates a slightly explosive mixture such that ignition under these conditions often shakes the boiler or furnace in which the burner is installed and in turn may shake the house. While this condition is usually not serious enough to be dangerous, it is very annoying and the present practice of oil burner service men in handling serious complaints involves the sacrificing of economy by making an excessive burner air or draft adjustment in order to correct such starting conditions. It is also pointed out that the initial oil flame due to this limited air supply on starting is smoky and unnecessary soot accumulation on the heating surface will naturally result.

It is, therefore, one object of my invention to provide an improved oil burner.

A further object of my invention is to produce an oil burner which will be free from the starting conditions referred to.

A further object of this invention is to produce an improved control mechanism for retarding the delivery of oil to the point of ignition until an adequate supply of combustion air has started to flow into the combustion chamber.

A still further object of my invention is to produce an improved control of the type set forth which is completely automatic and positive in its operation.

A still further object of my invention is to produce a control of the type set forth which is of a simple, dependable and inexpensive construction.

A still further object is to produce a control of the type set forth which is compact so that it may be easily added to conventional burners without materially increasing the overall dimensions or altering the general design thereof.

A still further object of my invention is to produce a control of the type set forth which can be

2

easily applied to oil burning apparatus already built and in use as well as to apparatus to be built in the future.

Accordingly, my invention provides movable means for receiving or making room for the initial supply of oil delivered by the pump when the burner is started, to delay the development of the pressure which opens the cut-off valve, said means being automatically returned to its original position when the burner is turned off.

These and other objects are effected by my invention as will be apparent from the following description and claims taken in connection with the accompanying drawings, forming a part of this application, in which:

Fig. 1 is a vertical cross-sectional view of an oil burner embodying my invention;

Fig. 2 is an enlarged sectional view on line II—II of Fig. 1; and,

Figs. 3, 4, and 5 are views similar to Fig. 2 showing modified forms of construction.

Figs. 1 and 2

Referring to the drawings, and more particularly to Fig. 1, there is shown a conventional oil burner including a casing 10 having a blast tube 12. In the casing 10 are mounted the usual blower 14, motor 16, gear pump 18, and conventional combined cut-off and pressure regulating valve 20. The blower 14 and pump 18 are driven by the motor 16 in any approved manner. In the blast tube 12 are the usual oil nozzle 22 and ignition elements 24. The ignition elements 24 are connected to a transformer 26 by wires 28 and the nozzle 22 is connected to the pressure regulating valve 20 by a tube 30. The discharge side of the gear pump 18 is connected by a passage 31 to a compartment 32, at one end of the regulating valve 20, and the inlet side of the pump is connected by a passage 33 to a compartment 34 at the other end of the pressure regulating valve 20. The inlet side of the pump is also connected by a pipe 35 to a supply tank (not shown).

The combined cut-off and pressure regulating valve 20 includes a piston 36 biased to the right by a spring 38, and a needle valve 40 biased in the opposite direction by a spring 42. One end 44 of the needle valve 40 is adapted to close a passage 45 which leads into the pipe 30, and the other end 47 of the needle valve 40 is adapted to close a passage 48 formed in the piston 36. The end 47 of the needle valve may be provided with a relief slot 46. The passage 45, when the needle valve is moved to the left in Fig. 2, communicates with the compartment 32 through ports 49. The movement of the needle valve 40

3

by the spring 42 is limited by abutment of the collar 58 against the nut 51.

With the conventional structure thus far described, no oil flows through the tube 30 and nozzle 22 until enough pressure is developed against piston 36 in the compartment 32 to move the piston 36 to the left against the action of the spring 38 and out of contact with the end 47 of the needle valve 40. The spring 42 now moves the needle valve 40 away from its seat to open the passage 45. But, due to the positive displacement of the oil, and the rapid action of the gear pump, the pressure necessary to displace the piston 36 is developed, and oil is discharged through the nozzle 22, well before the combustion air delivered by the blower 14 reaches its rated or normal flow through the blast tube 12.

In order to eliminate this condition and prevent explosive mixtures and improper combustion resulting from the initially inadequate supply of combustion air when the burner is started, I incorporate in the oil supply system an oil discharge delaying mechanism 52, one form of which is shown in Fig. 2. This mechanism comprises a cylinder 54, one end of which is connected by a pipe 56 to the discharge side of the pump 18, and the other end of which is connected by a pipe 58 to the pipe 35 or some other part communicating with the supply tank or the inlet side of the pump.

Within the cylinder 54 there is disposed a piston 60 which is exposed to oil pressure in the pipe 56. A spring 62 biases the piston to the right, the purpose of this spring being to move the piston to the right-hand end of the cylinder when the oil pump 18 is not operating. The force of the spring 62, which need be great enough only to move the piston to the right, is always such that the oil pressure developed by the pump in normal operation overcomes the force of the spring and moves the piston 60 to the left in Fig. 2. The stroke and bore of the piston, that is, the piston displacement, is such that a certain amount of time, such as, 1 or 2 seconds, more or less, will be required for the oil displaced by the pump to move the piston 60 from one end of the cylinder to the abutment 54.

Operation—Figs. 1 and 2

When the oil burner starts, oil is immediately displaced by the pump 18. Due to the lower resistance of the spring 62, the oil displaced by the pump 18 first displaces the piston 60 against the force of the spring 62, and the pressure in the compartment 32 is not enough to move the piston 36. In other words, the piston 60 is movable under a pressure of the oil which is less than the predetermined oil pressure at which the piston 36 is movable to open the valve 40.

When the piston 60 has been moved until it abuts against the stop 54, no more oil can be received by the cylinder 54 and the oil displaced by the pump now acts against the piston 36 to move it to the left. The spring 42 causes the needle valve 40 to follow the piston 36 until the collar 58 strikes the nut 51, thereby opening the passage 45. Oil now flows through the passage 45 and the pipe 30 to the nozzle 22.

The time consumed in moving the piston 60 through its travel should be sufficient to permit the combustion air to reach substantially its normal flow so that, when fuel oil begins to flow through the nozzle 22, the air supply will be adequate to produce proper soot-free combustion.

Since the pump 18 delivers more oil to the

4

compartment 32 than is required to maintain the desired pressure therein, which may be, for example, 100 pounds per square inch, the excess pressure of the oil will further move the piston 36 away from the end 47 of the needle valve 40 to open the passage 45. This permits the escape of enough oil to maintain the pressure in the compartment 32 at about 100 pounds per square inch. In this way, the pressure in the compartment is maintained substantially constant at the desired value. This value may be adjusted by turning the adjusting screw 65, the structure and operation of which are well understood in the art and hence need not be further explained here.

When the burner is turned off, pressure in the compartment 32 drops and the spring 38 actuates the piston 36 and the needle valve 40 to the right in Fig. 2 to shut off the flow of oil to the nozzle 22. In the absence of pressure, the spring 62 moves the piston 60 back to its starting position at the right-hand end of the cylinder 54, until the piston 60 abuts against the inner face of the nut 61. The parts are now in the position shown in Fig. 2 and the burner is ready to begin another cycle. The oil displaced by the return movement of the piston 60 slowly leaks past the gears of the pump 18 or through the relief slot 46 in the end 47 of the needle valve 40.

Fig. 3

30 In Fig. 3, I show a modified form of the construction shown in Fig. 2, in which the pipe 56, cylinder 54 and pipe 58 are omitted and replaced by another oil discharge delay device 70. The 35 discharge delay device 70 comprises a casing formed of a cup-shaped member 72 and a complementary closure member 74. The members 72 and 74 define a chamber 76 in which is disposed a diaphragm 78 clamped between two discs 80 and biased by a spring 82. In the member 74 is formed a recess 84 for accommodating the discs 80 and limiting the movement of the diaphragm 78. The closure member 74 is preferably provided with a test opening 88 normally closed by a screw 90. The casing 70 is secured to and communicates with the high pressure side of the pump 18 through a nipple or coupling 92.

Operation—Fig. 3

50 When the burner is turned on, the initial supply of oil delivered by the pump 18, moves the diaphragm 78 against the action of the spring 82, which is weaker than the spring 38. The movement of the diaphragm 78 from the solid to the 55 broken line position provides room for accommodating the initial discharge of oil, thus delaying development of pressure in the compartment 32 sufficient to overcome the spring 38. It will be noted that as the diaphragm 78 is moved across the chamber 76, the air in said chamber is compressed, thus forming a resilient cushion for said diaphragm. This resilient cushion assists the spring 82 in returning the diaphragm to its normal position when the burner is turned off. If it is desired to test the apparatus for leakage, the screw 90 is removed and the burner is turned on. Except as pointed out, the operation of this embodiment is otherwise the same as that described in connection with Fig. 2.

Figs. 4 and 5

In Figs. 4 and 5, I show two embodiments in which the oil discharge delay device, instead of being in the nature of a separate unit connected to the pump, as shown in Figs. 2 and 3, is incor-

porated in a combined cut-off and pressure regulating valve, such as that illustrated in Fig. 1 and commonly used in oil burners.

The embodiment shown in Fig. 4 includes a piston 94, a tube 96 and a collar 98 carried by one end of the tube 96. The piston 94 is slideable with respect to the casing of the pressure regulating and cut-off valve casing and the tube 96 and collar 98 are slideable within and relative to the piston 94. The piston 94 and collar 98 are biased in opposite directions by a spring 100 which is weaker than the spring 38 which biases the collar 98 and tube 96, and indirectly, the piston 94 to the right in Fig. 4. The other end of the tube 96 bears against and is closed by the end 47 of the needle valve 40. The interior of the tube 96 constitutes a passage corresponding to the passage 48 of Fig. 2. The piston 94 is provided with a cut-out 102 to reduce friction and facilitate its movement. The collar 98 is provided with an oil relief slot 104 and is adapted to be engaged by a shoulder 106 in the piston 94, when the piston 94 is moved to the left in Fig. 4. In its extreme right-hand position, the piston 94 abuts against a shoulder 95. Except as pointed out, the rest of the structure of the pressure regulating and cut-off valve is the same as that described in connection with Fig. 2.

Operation—Fig. 4

When the oil burner is started, the initial discharge of oil into the compartment 32 merely moves the piston 94 against the force of the spring 100 and thus makes room for accommodating the initial supply of oil discharged by the pump 18. Since the compartment 32 is in the path of the oil flowing from the gear pump 18 to the burner nozzle 22 through the passage 31, the compartment 32, the passage 45 and the tube 30, as will be seen in Fig. 4, it is apparent that there is no constriction between such flow path and the compartment 32. The compartment 32 may, therefore, be said to be in unconstricted communication with said flow path. Such unconstricted communication permits the oil to be received in the compartment 32 during the initial period of operation of the pump as rapidly as it is discharged from the passage 31 of such path. The force of the spring 38 being greater than that of the spring 100, even when the latter is compressed, the tube 96 is not moved, and the needle valve 40 remains in position to close the passage 45. When, under increased pressure, the piston 94 moves further, the shoulder 106 engages the collar 98, and the collar 98 and tube 96 are moved to the left against the force of the spring 38 to disengage the tube 96 from the end 47 of the needle valve 40. The relief slot 104 prevents undue accumulation of oil within the piston 94. Again, except as pointed out, the apparatus operates in the manner previously described in connection with Figs. 2 and 3.

The embodiment shown in Fig. 5 includes a relatively short piston 108 corresponding to the piston 94 and a separate stop 110 corresponding to the collar 98. The piston 108 and stop 110 slide within a fixed sleeve 112. The stop 110 is carried by one end of a stem 113, the other end of which slides through an opening in the head of the piston 108. A spring 114 biases the piston 108 and stop 110 in opposite directions while the spring 38 biases the stop 110, stem 113 and, indirectly, the piston 108 to the right in Fig. 5. The stop 110 is provided with a relief groove 115 which performs the same function as the relief groove 104 in Fig. 4. The piston 108 is provided with a

longitudinal relief groove 116 which terminates in an annular relief groove 118 formed in the outer surface of the piston 108. A portion of the groove 118 is adapted to register with a relief groove 120 formed in the sleeve 112 when the piston 108 is moved sufficiently to the left in Fig. 5 to displace the collar 110 and open the valve 122. The annular groove 118 is provided in order to eliminate the necessity of aligning the groove 116 with the groove 120. In this construction, the needle valve 40 and the port 48 are omitted and the passage 45 is closed by a valve head 122 carried by the other end of the stem 113 and coacting with a valve seat 124. The valve head 122 also serves as a stop for the piston 108 when the latter is in its extreme right-hand position.

Fig. 5—Operation

The initial discharge of oil into the compartment 32 moves the piston 108 against the action of the spring 114 until the piston abuts against the collar 110. During this time, the valve 122, under action of the spring 38, keeps the passage 45 closed and no oil flows through the pipe 30 to the burner nozzle. As the pump continues to deliver oil to the now enlarged compartment 32, the piston 108 moves the collar 110 to the left, thus moving the valve 122 away from its seat to open the passage 45. Further increase in pressure of the oil in the compartment 32 moves the piston 108 and collar 110 still further to the left and brings a portion of the groove 116 into registration with the relief groove 120. This permits some of the oil in the compartment 32 to escape through the relief outlet 33 to maintain the pressure in the compartment 32 substantially constant, in a manner similar to that described in connection with Figs. 1 and 2.

It will thus be seen that the action of my oil discharge delay mechanism creates a sufficient lag or delay in the arrival of the fuel oil at the point of combustion, until the motor energizing the fuel pump and the blower has come up to speed and the combustion air delivered to the combustion chamber has reached its rated flow, or a satisfactory adequate volume.

My invention is especially useful for delaying the discharge of oil in a construction in which the blower and the pump are driven by the same motor as distinguished from apparatus using separate motors for driving the blower and the pump, with the motor driving the pump being energized after the energization of the motor driving the blower.

It will further be seen that I have devised a simple, inexpensive, and compact oil discharge delay mechanism which can be added to oil burners already installed and in use, as shown in Fig. 2, and which can be incorporated in the standard pressure regulator forming part of conventional oil burners without greatly modifying its standard construction and design. It will also be seen that the oil discharge delay described can be incorporated in a conventional pressure regulating and cut-off valve without materially increasing its overall dimension or the weight thereof.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. In an oil burner including a blower for delivering combustion air to the combustion chamber of said burner, a nozzle for delivering fuel oil to said combustion chamber, a positive displacement pump for delivering oil under pressure to said nozzle, a single motor for driving said blower and said pump, and a valve controlling the flow of oil through said nozzle, valve control and discharge delay mechanism comprising spring-biased means controlling said valve and normally assuming a first position in which said valve is closed, means responsive to oil pressure from said pump of a predetermined value for moving said spring-biased means to a second position in which said valve is open, and pressure-responsive means subjected to the pressure of the oil and movable through a limited range, independently of said spring-biased means, under pressure less than the said predetermined pressure value, the movement of said last-mentioned pressure-responsive means providing room for accommodating the oil initially discharged by said pump to delay the opening of said valve until the air delivered by said blower to said combustion chamber has reached substantially its normal flow.

2. The structure recited in claim 1 together with means for returning said pressure-responsive means to its initial position when the flow of oil is cut off.

3. In an oil burner including a blower for delivering combustion air to the combustion chamber of said burner, a nozzle for delivering fuel oil to said combustion chamber, a positive displacement pump for delivering oil under pressure, means defining a flow path for said oil from the discharge side of said pump to said nozzle, a single motor for driving said blower and said pump, and a valve controlling the flow of oil through said nozzle, valve control and discharge delay mechanism comprising spring-biased means adapted to be subjected to the pressure of said oil for controlling said valve and normally assuming a first position in which said valve is closed, said spring-biased means being movable by the oil pressure, when said oil pressure has reached a predetermined value, to a second position in which said valve is open, and means for delaying the opening of said valve to permit combustion air delivered to said combustion chamber to reach substantially its normal flow, before any oil is discharged through said nozzle to said combustion chamber, including a compartment having unconstricted communication with said flow path, a plunger in said compartment, means biasing said plunger in a direction to oppose the admission of oil into said compartment, said biasing means being of such strength as to yield under a pressure less than said predetermined pressure value to open said compartment for receiving the initial amount of oil delivered by said pump, thereby delaying the development of said predetermined pressure value against said pressure-responsive means.

4. In an oil burner including a blower for delivering combustion air to the combustion chamber of said burner, a nozzle for discharging oil to said combustion chamber, a positive displacement pump for delivering oil under pressure to said nozzle, a single motor actuating said pump and said blower, and a valve for controlling the flow of oil from said pump to said nozzle, valve control and discharge delay mechanism comprising a spring-biased element normally engaging and urging said valve to closing position to pre-

vent the flow of oil through said nozzle, said spring-biased element being movable by oil pressure from said pump of a predetermined value in valve opening direction, and means for delaying the movement of said spring-biased element and the opening of said valve, to delay the flow of oil through said nozzle until the air delivered by said blower has reached its normal flow, including a plunger subjected to the pressure of oil delivered by said pump and movable by oil pressure less than said predetermined pressure value through a limited range independently of said spring-biased element, the movement of said plunger through said limited range providing room for receiving the initial amount of oil delivered by said pump and thus delaying the development of said predetermined pressure value and the opening of said valve, said plunger being movable beyond said limited range when the oil pressure has reached said predetermined value to engage said spring-biased element and actuate the same in valve opening direction.

5. A delayed opening flow control device comprising a casing having a fluid inlet and a fluid outlet, a valve for controlling flow of fluid from said inlet to said outlet, a spring biasing said valve to open position, a spring-biased member normally engaging and maintaining said valve in closed position against the force of said spring, a plunger subjected to the pressure of fluid entering said casing through said inlet, and a spring biasing said plunger against the pressure of said fluid with a predetermined force value, said plunger being movable through a limited range, and independently of said spring-biased member, by the pressure of said fluid, when said pressure exceeds said predetermined value, to provide room for a portion of said fluid, said plunger being further movable, upon further increase in fluid pressure, to contact and move said spring-biased member in valve opening direction, to permit opening of said valve by said first-mentioned spring.

6. A delayed opening flow control device comprising a casing having a fluid inlet and a fluid outlet, a valve for controlling flow of fluid from said inlet to said outlet, a spring-biased member normally engaging and maintaining said valve in closed position, a plunger subjected to the pressure of fluid entering said casing through said inlet, a spring biasing said plunger against the pressure of said fluid with a predetermined force value, said plunger being movable through a limited range, and independently of said spring-biased member, by the pressure of said fluid, when said pressure exceeds said predetermined value, to provide room for a portion of said fluid, said plunger being further movable, upon further increase in fluid pressure, to contact and move said spring-biased member in a valve opening direction, and a by-pass operative in response to further movement of said plunger, after said valve has opened, for by-passing a portion of the fluid flowing from said inlet to said outlet.

- 65 7. A delayed opening flow control device comprising a casing having a fluid inlet and a fluid outlet, a valve for controlling flow of fluid from said inlet to said outlet, a spring-biased member normally engaging and maintaining said valve in 70 closed position, a plunger subjected to the pressure of fluid entering said casing through said inlet, a spring biasing said plunger against the pressure of said fluid with a predetermined force, said plunger being movable through a limited 75 range, and independently of said spring-biased

member, by the pressure of said fluid, when said pressure exceeds a predetermined value, to provide room for a portion of said fluid, said spring-biased member being movable by the pressure of said fluid when it reaches a greater predetermined value to permit opening of said valve after said plunger has moved through its limited range, and a by-pass operative in response to further movement of said spring-biased member after said valve has opened, for by-passing a portion of the fluid flowing from said inlet to said outlet.
